US0D1031429S

(12) **United States Design Patent** (10) **Patent No.:** **US D1,031,429 S**
(45) **Date of Patent:** **** Jun. 18, 2024**

(54) **BLANK FOR CARTON**

(71) Applicant: **Elopak ASA**, Spikkestad (NO)

(72) Inventors: **Øyvind Eckhoff**, Sande i Vestfold (NO); **Vegard Holm**, Sande i Vestfold (NO)

(73) Assignee: **Elopak ASA**, Spikkestad (NO)

(**) Term: **15 Years**

(21) Appl. No.: **35/514,500**

(22) Filed: **Dec. 20, 2021**

(80) **Hague Agreement Data**

Int. Filing Date: **Dec. 20, 2021**

Int. Reg. No.: **DM/218815**

Int. Reg. Date: **Dec. 20, 2021**

Int. Reg. Pub. Date: **Jun. 24, 2022**

(51) **LOC (14) Cl.** **09-03**

(52) **U.S. Cl.**

USPC **D9/431**

(58) **Field of Classification Search**
